UNITED STATES PATENT OFFICE

EUGENE M. SCOVILLE, OF MILWAUKEE, WISCONSIN, ASSIGNOR OF ONE-HALF TO
FLOYD L. SWANBERG, OF PITTSBURGH, PENNSYLVANIA

PUMP

Application filed October 20, 1924. Serial No. 744,802.

This invention relates in general to improvements in the art of propelling fluid by positive displacement, and relates more specifically to improvements in the construction and operation of single and double acting reciprocable positive displacement pumps for fluids.

A general object of the invention is to provide an improved pump structure which is simple in construction and efficient in operation.

Some of the more important specific objects and advantages accruing from the present improvements, are as follows:

15 To provide a simple and ingenious pump structure which may be readily and quickly converted from a single acting unit into a double acting unit of increased capacity, and vice versa.

20 To provide a compact and efficient pump having relatively large and conveniently variable capacity.

To provide improved liquid pumping mechanism which may be manufactured at minimum cost, and all portions of which are easily accessible for machining.

25 To provide a pumping device in which similarly functioning elements are identical in form and are therefore interchangeable.

30 To provide an improved pump structure every part of which is readily accessible and quickly removable, and which may be conveniently assembled or dismantled.

To provide improved casing, plunger and 35 valve structures for reciprocable liquid pumps.

To provide improved means for insuring proper lubrication of pumping machinery.

30 To provide other improvements in the details of construction, assemblage and operation of pumping mechanisms, whereby commercial manufacture thereof is greatly facilitated and whereby the efficiency of such mechanisms is enhanced to a maximum.

45 These and other objects and advantages of the present improvement should be apparent in the course of the following detailed description.

Some of the novel features of pump structure and driving mechanism therefore, dis-

closed but not specifically claimed herein, form the subject of a copending application Serial Number 741,881, filed October 6, 1924.

A clear conception of embodiments of the several novel features constituting the present improvement, and of the operation and mode of assembling and dismantling devices constructed in accordance with the invention, may be had by referring to the drawings accompanying and forming a part of this specification in which like reference characters designate the same or similar parts in the various views.

Fig. 1 is a central vertical section through an improved liquid pump assembled as a single acting unit.

Fig. 2 is a side elevation of the improved liquid pump assembled as a single acting pump.

Fig. 3 is a part sectional top view of the improved liquid pump with the top casing section removed.

Fig. 4 is a transverse horizontal section through the lower casing section of the improved liquid pump.

Fig. 5 is an end elevation of the improved liquid pump assembled as a single acting unit and having a continuous rotary drive applied thereto.

Fig. 6 is a transverse central vertical section through an improved liquid pump converted into a double acting unit and having an oscillatory drive applied thereto.

Fig. 7 is a full top view of the improved liquid pump converted into a double acting unit.

Fig. 8 is a fragmentary side elevation of the improved oscillatory pump drive.

Fig. 9 is a top view of one of the elements of the improved oscillatory pump drive.

The improved liquid pump specifically shown in the drawings comprises in general a main casing consisting of a lower or base section 2 and an upper or top section 3 having vertical aligned bores therein; rigidly connected lower and upper plungers 5, 4 snugly fitting the bores of the casing sections 2, 3, respectively; a plunger actuating cam 6 coacting with end surfaces of the plungers 4, 5 between the bores in the casing sections 2, 3; a hori-

zontally disposed main driving shaft 7 supported in bearings 23, 47 detachably secured to the casing section 2, and having a polygonal medial portion coacting with a hole in the cam 6; means for actuating the shaft 7 to move the cam 6 and the plungers 4, 5; and liquid admission and discharge valves 10, 11, 24, 25 cooperable with the plungers 4, 5.

The base section 2 of the main casing is provided with a sole plate and a lower displacement chamber 22 below the end of the vertical bore therein, and has inlet and discharge chambers 46, 43 respectively which are communicable with the displacement chamber 22 through a common passage 13. An inlet or suction pipe 8 is in open communication with the inlet chamber 46 and a spherical suction valve 10 controls the passage of liquid from the chamber 46 to the passage 13 and chamber 22. An outlet or discharge pipe 9 is in open communication with the discharge chamber 43 and a spherical discharge valve 11 which coacts with a removable seat 17, controls the delivery of liquid from the passage 13 to the chamber 43. The valve seat 17 provides a stop for limiting the opening movement of the suction valve 10, the valve 10 being freely vertically removable upon removal of the seat 17, and the seat 17 and the discharge valve 11 being freely vertically removable upon removal of the plug 18 which normally encloses the chamber 43 and forms a stop for limiting the opening movement of the valve 11.

The base section 2 and the top section 3 of the casing are detachably connected by means of cap screws 42 and cooperate to form a chamber 41 between the plungers 4, 5. The top section 3 of the casing is provided with an upper displacement chamber 44 which is normally closed by means of a solid plug 21 when the pump is assembled as a single acting unit. The base section 2 of the casing is provided with an opening 15 communicating with the chamber 41, this opening being normally closed by means of a pipe plug 16 when the pump is assembled to operate single acting. The top section 3 is also provided with a horizontally bored lug 12, the function of which will be later explained.

The lower pump plunger 5 which cooperates with the lower displacement chamber 22 is formed solid, while the upper pump plunger 4 which is adapted to cooperate with the upper displacement chamber 44 has a vertical central bore 20 and a transverse passage 19 formed therein. The bore 20 and the passage 19 provide an open conduit connecting the chambers 41, 44 when the pump is assembled to operate single acting. The plungers 4, 5 are rigidly connected by means of connectors 14 and are freely removable from within the main casing upon removal of the screws 42 and separation of the sections 2, 3.

The plunger actuating cam 6 located within

the chamber 41 is formed to maintain constant coaction with the parallel adjacent end surfaces of the plungers 4, 5. The cam 6 has a polygonal hole which coacts with the medial polygonal portion of the main driving shaft 7, the shaft 7 being freely endwise removable from within the cam 6. One end of the shaft 7 is supported in a removable closed bearing 23 and the opposite end portion penetrates a removable open bearing 47 and extends some distance beyond the stuffing box 48. The bearings 23, 47 are interchangeably cooperable with threaded openings formed in opposite sides of the base section 2, thereby permitting reversal of the shaft 7 relatively to the main casing.

When the pump is assembled for operation as a double acting unit as shown in Figs. 6 and 7, a suction pipe connects with the opening 15 in the lower section 2 and a spherical suction valve 24 is disposed within the bore 20 of the hollow plunger 4. The solid plug 21 is replaced by a discharge valve cage 26 within which a spherical discharge valve 25 is located. A discharge pipe 28 is connected to the valve cage 26 by means of a fitting 27 which besides forming a stop for limiting the opening movement of the valve 25, permits access to the valve.

The oscillatory driving mechanism for moving the cam 6 to reciprocate the pistons 4, 5, shown in Figs. 6, 8 and 9, comprises a slotted adjusting quadrant 31 keyed to the outer end of the shaft 7, an actuating arm 29 pivotally supported by the shaft 7 and adjustably secured to the quadrant 31 by means of a locking cap screw 32, a bifurcated connection 30 formed for pivotal connection with any one of several openings 39 of the lever 29 by means of a pin 40, and a reciprocable rod 45 secured to the connection 30. The continuous rotary driving mechanism for moving the cam 6, shown in Fig. 5, comprises a spur gear 38 secured to the outer end of the shaft 7, a pinion 37 meshing with the gear 38 and secured to one end of a counter shaft 34, a driving sheave 33 secured to the opposite end of the counter shaft 34, a bearing bushing 35 coacting with the bored lug 12 of the top casing section 3, and a nut 36 for locking the bushing 35 in position.

During normal operation of the pump as a single acting unit, the structure is assembled as shown in Figs. 1 and 2 and may have either the oscillatory or the continuous rotary drive applied. As the cam 6 is moved, it coacts with the adjacent end surfaces of the plungers 4, 5 and produces simultaneous but opposite reciprocation of these plungers in the respective bores of the casing sections 2, 3. The reciprocating solid lower plunger 5 alternately enters and recedes from the lower displacement chamber 22 thus drawing liquid from the pipe 8 through the chamber 46 and past the suction valve 10 into the passage

13 and subsequently forcing the liquid past the discharge valve 11 through the chamber 43 and into the discharge pipe 9. The reciprocating hollow upper plunger 4 is inactive with the elements thus assembled. If the structure is assembled for double acting operation as shown in Fig. 6, the reciprocating hollow upper plunger 4 becomes active and alternately draws liquid from the pipe which communicates with the opening 15 through the chamber 41, passage 19 and bore 20 past the suction valve 24, and subsequently forces the liquid from the displacement chamber 44 past the discharge valve 25 into the upper discharge pipe 28. It will thus be apparent that the structure is readily convertible from single acting with only the lower plunger 5 active, to double acting with both plungers 4, 5 active, and vice versa.

20 The spherical suction and discharge valves 10, 11, 24, 25 are identical in structure thus making them interchangeable, and these valves are readily accessible by virtue of the removable seat 17, cap 18, fitting 27 and cage 25. The removable bearings 23, 47 permit free removal of the shaft 7 whereupon the plungers 4, 5 and the cage 6 are readily removable by releasing the cap screws 42. By providing independent inlet and discharge 30 pipes 8, 9, 15, 28 the plungers 5, 4 may be utilized to urge different kinds of liquid, but the discharge pipes 9, 28 may be connected to cause both plungers to pump against a common head. The various elements of the 35 structure are obviously conveniently machinable and the entire mechanism may be quickly assembled or dismantled. The liquid pumped may obviously be oil, in which case the plungers 4, 5 are effectively lubricated by the oil passing through the chamber 41 to the upper displacement chamber 44. The capacity of the unit may be readily varied by varying the speed of operation or by changing from single to double acting, and the 45 stuffing box 48 effectively prevents escape of liquid from the chamber 41. Either type of driving mechanism may be applied to the pump thus permitting utilization of either reciprocating or rotary power.

50 It should be understood that it is not desired to limit the invention to the exact details of construction and operation herein shown and described, for various modifications within the scope of the claims may occur to persons skilled in the art.

It is claimed and desired to secure by Letters Patent:—

1. In combination, a casing forming a pair of aligned displacement chambers and an enlarged intervening space, rigidly connected plungers movable within said chambers and having parallel adjacent end surfaces within said space, one of said plungers being solid and the other having a longitudinal passage 65 connected with said space by a lateral passage

disposed closely adjacent to said end surface thereof, rotary means within said space and cooperable directly with said end surfaces to reciprocate said plungers in said chambers, inlet and discharge valves in said casing for controlling the flow of fluid to and from the displacement chamber of said solid plunger, conduit means for admitting fluid to said space, an inlet valve within said passage of said other plunger for controlling admission of fluid from said space to the displacement chamber of said other plunger, and a discharge valve associated with said casing for controlling the delivery of fluid from the displacement chamber of said other plunger.

2. In combination, a sectional casing forming a pair of aligned displacement chambers and an enlarged intervening space, the sections of said casing being separable at said space, rigidly connected plungers movable within said chambers and having adjacent end surfaces within said space, one of said plungers being solid and the other having a longitudinal passage connected at one end with said space, rotary means within said space and cooperable directly with said surfaces to reciprocate said plungers in said chambers, an inlet valve in said casing for controlling admission of fluid to the displacement chamber of said solid plunger, conduit means for admitting fluid to said space, an inlet valve within said passage for controlling admission of fluid from said space to the displacement chamber of said other plunger, and valve means associated with said casing for controlling delivery of fluid from said chambers.

3. In combination, a casing forming a pair of aligned displacement chambers and an intervening space, interconnected plungers movable within said chambers and having adjacent end surfaces within said space, one of said plungers being solid and the other having a longitudinal passage connected at one end with said space, rotary means within said space and cooperable with said surfaces to reciprocate said plungers in said chambers, inlet and discharge valves in said casing for controlling the flow of fluid to and from the displacement chamber of said solid plunger, conduit means for admitting fluid to said space, a freely removable inlet valve within said passage for controlling admission of fluid from said space to the displacement chamber of said other plunger, a discharge valve detachably associated with an opening in said casing for controlling delivery of fluid by said other plunger, and means for sealing said conduit means and said casing opening when said inlet valve is removed from within said plunger passage.

4. In combination, a casing forming vertically aligned displacement chambers and having conduit means communicating with the

space between said chambers, plungers simultaneously movable within said chambers, one of said plungers being solid and the other having a longitudinal passage communicating at one end with said conduit means and at its opposite end with an opening in said casing, means within said space for reciprocating said plungers in said chambers, inlet and discharge valves for controlling the flow of fluid to and from the displacement chamber of said solid plunger, a freely removable ball inlet valve for controlling admission of fluid from said conduit means to the displacement chamber of said other plunger, a discharge valve detachably associated with said casing opening for controlling delivery of fluid by said other plunger, and means for sealing said conduit means and said casing opening when said ball valve is removed.

In testimony whereof, the signature of the inventor is affixed hereto.

EUGENE M. SCOVILLE.
